UNITED STATES PATENT OFFICE.

CLARENCE B. HARBISON, OF LIMA, OHIO, ASSIGNOR TO THE OHIO STEEL FOUNDRY CO., OF LIMA, OHIO, A CORPORATION OF OHIO.

CAST-STEEL TENDER FRAME.

Application filed January 12, 1927. Serial No. 180,548.

This invention relates to improvements in car frames, and more particularly to locomotive tender frames, although not necessarily restricted to such use.

5 Among the objects of the invention is to provide an improved main frame formed in a single casting including bolsters, end frame members and a center supporting member, with integral flooring board securing strips carried by the latter, and further, to provide jacking pieces secured to the ends of the bolsters so as to permit the entire body to be raised from the car trucks when desired.

The invention may best be understood by 15 reference to the accompanying drawings, in which

Figures 1^A and 1^B together constitute a plan view of a tender frame constructed in accordance with my invention.

20 Figures 2^A and 2^B together show a longitudinal section of the frame shown in Figures 1^A and 1^B.

Figure 3 is a section of a bolster taken on line 3—3 of Figure 1^A.

25 Figure 4 is a detail of a jacking piece adapted to be secured on the end of the bolster.

Figure 5 is a bottom view of the bolster end to which a jacking piece may be secured.

30 Figure 6 is a bottom view of a jacking piece.

Figure 7 is a modified form of bolster having a jacking piece formed integral therewith.

35 Referring now to details shown in the drawings, the tender frame illustrated comprises a centrally disposed longitudinal beam 10, bolsters 11—11, end frame members 12—12 and an intermediate transverse sup-

40 porting piece 13—13. All of the parts above mentioned are preferably formed in a single piece casting, as shown, the main beam 10 and bolster 11 being generally a hollow box-like structure, as clearly shown in Figures 2^A, 2^B and 3. The bolsters 11—11 are

45 provided with bearing apertures 15—15 adapted to receive the central bearing pin of the truck in the usual manner. Portions of the trucks are not shown herein, as they

50 form no part of the present invention. Suitable reinforcing means are provided adjacent the bolsters 11—11, herein comprising centrally disposed webs 16—16 formed in the side walls of the main longitudinal beam 10

adjacent its points of junction with the two 55 bolsters.

Along the top surface of the single piece main frame casting and extending longitudinally of the main beam 10 to points adjacent the end bars 12—12, I provide a plurality of interlocking strips 20—20 formed as an integral part of the main casting. These strips project upwardly and are adapted to engage in corresponding grooves formed in the usual floor boards of the tender 60 65 so as to restrain them from lateral displacement. In the form shown, two of such interlocking strips 20—20 are shown, and in Figure 3 the position of the overlying floor boards are indicated at 21 by means of 70 dotted lines. It will be understood, of course, that any number of such interlocking strips may be utilized, and that the relative arrangement and width of the boards may be varied widely from that shown. 75

In connection with the bolsters 11—11 which are formed integrally and have reinforced connection with the remaining portions of the main frame casting, I provide a pair of jacking supports 25—25 forming 80 lateral extensions of the bolsters 11—11. In the form shown in Figure 3, these jacking supports are formed of separate castings having a horizontal bearing surface 26 and an inclined connecting plate 27 by means of 85 which the support is detachably secured to a cooperating supporting face 28 formed on the extreme end of the bolster 11. In the preferred form shown, the bolster is provided with a shoulder 29 at the upper end of 90 the supporting face 28 against which the supporting face 28 fits when the support is attached, as shown. The arrangement is such that the horizontal jacking surface 26 projects laterally in position to be readily 95 engaged by a hoisting jack of the usual form, for this purpose, of course, the projection being sufficient to clear the side of the track rails and truck.

In the modified form shown in Figure 7, 100 the jacking support 30 is shown formed integral with the bolster 11.

From the above description of the jacking support it will be seen that the latter is attached directly to the bolster in position to 105 be engaged by a jack and lift the entire main frame from the truck when desired. The entire structure affords a most substan-

tial main frame casting, without the usual provision of side-sills, and yet having means suitable for jacking the entire frame, through the bolsters themselves.

5 I claim as my invention:

In a car or tender, a main frame comprising a central longitudinally disposed main beam, bolsters, and end frame members all formed in a single piece casting, and a plu-

rality of interlocking strips formed integrally along the upper surface of said main beam and adapted to have interlocking engagement with the floor boards laid thereover.

Signed at Lima, Ohio, this fourth day of 15 January, 1927.

CLARENCE B. HARBISON.
